UNITED STATES PATENT OFFICE.

GEORG SULZER, OF BUFFALO, NEW YORK, ASSIGNOR TO BUFFALO FORGE COMPANY, OF BUFFALO, NEW YORK.

CENTRIFUGAL PUMP.

No. 800,968.

Specification of Letters Patent. Patented Oct. 13, 1908.

Application filed December 9, 1905. Serial No. 291,005.

To all whom it may concern:

Be it known that I, GEORG SULZER, a citizen of the Swiss Republic, residing at Buffalo, in the county of Erie and State of New York, have invented a new and useful Improvement in Centrifugal Pumps, of which the following is a specification.

This invention relates more particularly to centrifugal pumps of the multiple stage type in which a plurality of impellers are arranged side by side to rotate together and are so constructed, arranged and connected by water ways that the water is drawn into the inlet at the center of the first impeller from the suction pipe and after being thrown out from the peripheral discharge orifices of this impeller is returned to the inlet of the next impeller, being thus passed through all of the impellers in succession, whereby the water pressure is built up in proportion to the number of impellers employed.

Certain features of the invention, however, notably the packing rings for the joints between the impellers and stationary parts of the pump, are not restricted to multiple stage pumps, but are applicable in other machines.

One of the principal objects of the invention is to so arrange the water ways in a balanced piston multiple stage pump that the water is passed through the pump with the fewest changes of direction and by the shortest course consistent with gradual easy turns in the water passages, whereby the internal friction and leakage are reduced to the minimum and the efficiency of the pump increased.

Other objects of the invention are to so construct and arrange the casing, impellers, diffusing rings, and disks separating the impellers and forming the return passages, that all of the impellers, rings and disks can be assembled on the impeller shaft outside of the casing and can be inserted into and removed from the casing as an entity and without disturbing the pipe connections of the pump; to form the casing and removable parts so that the latter can be placed in and removed from the former more quickly and with less exertion than heretofore; and to provide an efficient, practical and durable means for packing the joints between the rotary impellers and stationary parts of the pump.

Other objects of the invention will appear from the following description.

In the accompanying drawings, consisting of five sheets: Figure 1 is a longitudinal sectional elevation of a multiple stage balanced piston centrifugal pump embodying the invention, taken in line 1—1, Fig. 2. Fig. 2 is a transverse sectional elevation thereof, on an enlarged scale, in line 2—2, Fig. 1. Fig. 3 is a transverse section thereof, on an enlarged scale, in line 3—3, Fig. 1. Fig. 4 is a transverse section thereof, on an enlarged scale, in line 4—4, Fig. 1. Fig. 5 is a fragmentary longitudinal sectional elevation thereof, on an enlarged scale, in line 5—5 indicated in Figs. 2, 3 and 4. Fig. 6 is a fragmentary section in line 6—6, Fig. 5, showing the packing ring in elevation. Fig. 7 is a section of the packing ring, on an enlarged scale, in line 7—7, Fig. 6. Fig. 8 is a sectional elevation of the pump shell.

Like letters of reference refer to like parts in the several figures.

A represents the casing or cylinder of a multiple stage centrifugal pump, B B' B² and B³ the rotary impellers which are mounted to rotate together on a shaft C.

Preferably the pump casing consists of a hollow shell or body, one end of which is closed by a head A' removably secured to the shell by bolts a or other means, and in the construction shown in the drawings a removable head A² is also provided for the other end of the casing, and the shell is mounted on or provided with a suitable base a'. The head A² is provided with an annular suction chamber a² and a communicating connection a³ for the suction pipe (not shown), and the shell is provided near its opposite head with a discharge pipe or connection a⁴.

The impellers are of ordinary form, consisting of hollow circular bodies provided at one side with central annular suction or inlet openings b, Fig. 5, and with peripheral discharge orifices, and having the usual internal impelling vanes or blades b', Fig. 2. The impellers are mounted in pairs on the shaft C with the impellers of each pair arranged oppositely, or with their suction openings at their far sides and facing in opposite directions, so that the water pressure will be in opposite directions on the two impellers and thereby in large measure

balance the end thrust on the impeller shaft. A four-stage pump, having two pairs of impellers thus arranged, is shown in the drawings but the invention is equally applicable 5 to pumps of two, six or any other even number of stages. The impeller shaft passes through central shaft openings in the heads A' A² of the casing and is journaled at its opposite ends in bearings D D' of any usual 10 or suitable construction. The bearing D is shown as supported by a standard fixed on the base a' of the pump, while the other bearing D' is preferably secured by a bracket or arm d to the removable head A' 15 of the casing at the pressure side of the pump so that said head and shaft, together with the impellers and other removable parts of the pump, to be hereinafter described, can be removed from the casing 20 without separately removing the shaft bearing D'. The impellers are keyed or otherwise connected to the shaft C to turn therewith and they are removably secured against endwise movement on the shaft between 25 bushings e and e' by a clamping sleeve e² which is screwed on a threaded portion of the shaft. The bushing e abuts against a shoulder e³ on the shaft. The pairs of impellers are spaced apart by a bushing e⁴ interposed between the hubs of the adjacent impellers of the pairs and the bodies of the two impellers of each pair are held apart the necessary distance by the engagement of 30 their hubs. Stationary partition walls or 35 disks F are arranged between the impellers of each pair and stationary walls or disks F' F² are arranged respectively between the pairs of impellers and between the last impeller B³ and the head A' at the pressure 40 side of the pump. The disks F are solid, that is they have no water passages, while the disk F² is hollow, forming return passages f for the impeller B' of one pair and return passages f' for the impeller B² of the 45 next pair, and the disk F² is provided with return passages f for the last impeller.

G represents stationary diffusing rings. As usual, one of these diffusing rings surrounds each impeller between the same and 50 the shell, forming a running joint with the impeller, and is provided with passages g which expand or increase in width from the inner edge of the ring to the outer edge thereof to reduce the velocity of the water 55 forced out through them by the impeller. The restricted inner ends of the passages of the several diffusing rings are directly opposite to the peripheral discharge orifices of the impellers and their enlarged ends are 60 disposed opposite to and communicate directly with surrounding annular chambers H H' H² H³ formed in the shell A of the casing. The shell is also provided with longitudinal canals h, Figs. 1, 2, 3 and 8, 65 which connect at one end with the shell

chambers H H² opposite the first impeller of each pair and have inturned ends directly opposite the return passages f in the partition disks for the other impeller of each pair. In the pump illustrated there are four 70 of these canals h for each shell chamber H and H² disposed at equal distances around the shell and four return passages f communicating therewith are provided in each disk F' and F². The particular number of 75 canals and return passages is immaterial, however, it being only essential that the canals be sufficient in number and size to take care of the water discharged by each impeller. The canals h extend into or through the other shell chambers H' and H³ and the spaces left in these chambers between the canals h afford direct communications between the diffusing ring for the second impeller of one pair and the return passages or 80 chambers f' leading to the suction of the first impeller of the next pair.

By reason of the described arrangement of the canals and intermediate spaces connecting the shell chambers and return passages the water passes by a very short and direct course, and with only one change of direction from the diffusing ring of one impeller to the suction inlet of the next impeller. The water from one impeller of a 90 pair passes around or outside of the companion impeller and diffusing ring, and the two impellers of each pair can be located close together without necessitating the water to make sudden and sharp changes of direction. 100

The most efficient multiple stage pump is that in which the water has the shortest and most direct course from the suction pipe to the discharge pipe, and many attempts have 105 been made to shorten the water courses and free them from angles and turns, but it has been a matter of difficulty to secure these results and at the same time produce a multiple stage balanced piston pump of compact 110 construction. In nearest approaches to the construction described of which I am aware, the water describes a compound or S curve in its passage from one impeller to the next of a balanced pair, in one known instance 115 passing out through the diffusing passages of the diffusing ring and then turning back and laterally through holes in the diffusing ring and then making another turn in entering the return passage to the companion 120 impeller. In another instance, the water passes from the diffusing ring of one impeller through a space between the impellers before entering the return passage of the companion impeller, describing a compound 125 curve between the diffusing ring and return passage. As every change of direction adds to the friction and leakage, the short direct water courses produced by this invention greatly increase the efficiency of the pump. 130

- The discharge pipe a^4 of the pump leads from the last annular shell chamber H^2 . The several diffusing rings and stationary disks which separate the impellers of each 5 pair and form the return passages are clamped together and to the removable head A' of the casing by long bolts I , Figs. 1-4, which pass through the several parts and are provided with nuts i at their ends. 10 These bolts are distinct from the bolts a which secure the head A' to the shell and are only for holding the removable parts together. The impellers, disks and diffusing rings can all be assembled on the shaft C 15 with the head A' outside of the casing shell and then slipped into the shell and the head A' secured in place by means of its bolts a . As the bearing D' for the shaft is attached to the removable head A' it is only 20 necessary, in order to remove the several parts from the shell, to remove the bolts a and pull the head A' with the shaft and parts carried thereby out of the shell. 25 The diffusing rings and stationary disks or walls are fitted to and rest in annular seats k formed on the walls of the shell which 30 separate the annular water chambers, and the removable head A' fits in an annular seat k' at the end of the shell. To further facilitate the insertion and removal of the assembled 35 parts into and from the shell, each seat in the shell for the rings, disks and removable head is slightly smaller in diameter than the next seat toward the removable head, the seat for the diffusing ring at one end of the 40 shell being smallest and the seat for the removable head at the opposite end of the shell being largest. The difference in diameters of the seats k k' is small and is best indicated by comparing the distances of the several 45 seats from the broken line X , Fig. 8, which is coincident with the seat k' for the head A' . On account of the difference in the diameters of the seats in the shell the parts 50 can be moved into the shell freely and without pressure, until each ring and disk and the removable head reaches its particular seat, after which a comparatively short movement of the parts by pressure on the removable head will force all of the parts into 55 their seats. A similar short movement of the parts will free all of them from their seats and permit them to be then pulled out of the shell with little exertion. Screws l , 60 Fig. 1, working in threaded holes in the head A^2 of the casing and abutting against the adjacent diffusing ring are preferably employed for thus starting the parts from their seats. 65 To insure the fitting of the diffusing rings and stationary disks in their several seats in the shell, the several diffusing rings are fitted to annular shoulders m on the head A^2 of the casing and on the hollow disks F' and F^2 and the diffusing rings have annular

shoulders m' fitted to coöperating shoulders on the other stationary disks F . Likewise the hollow disk F^2 at the pressure side of the pump and the removable head A' have fitting shoulders m^2 . Thus the disks and diffusing rings can be accurately centered when assembled and will properly fit when inserted in the shell.

Leakage at the joints between the hubs of the impellers and stationary disks is prevented by packing rings preferably constructed as shown in Figs. 5, 6 and 7. Each packing ring N surrounds the hub of the impeller, the inner diameter of the ring being finished of such size that the hub can turn freely and without friction therein and with so little clearance between the ring and hub as to practically prevent the escape of water through the joint. The packing ring is secured to the disk or stationary part of the pump forming with the impeller hub the joint to be packed, so that while it is held from turning with the impeller it is allowed to shift slightly, both laterally and longitudinally. As shown, the packing ring is confined loosely in a flanged supporting ring n which is fixed from movement in an annular recess n' in the stationary disk or part and is connected to the supporting ring by screws n^2 . The stems of the screws are of smaller diameter than the holes in the packing ring N through which they pass, and are shouldered so that they cannot be driven in far enough for their heads to engage the packing ring and clamp it against the supporting ring n . The packing ring can therefore shift on the screws, both laterally and longitudinally, and instead of the hub of the impeller shifting in the packing ring and wearing the same when the bearings for the impeller wears and it does not run perfectly true, the ring will shift with the impeller. The wear on the inner face of the packing ring is, therefore, largely reduced and the ring will last for a long period before the clearance between it and the impeller will increase sufficiently to cause a harmful leakage between the packing ring and the impeller hub.

The pressure of the water in the space between the body of the impeller and the inner end of the packing ring is greater than that which prevails in the joint between the impeller hub and stationary disk or part of the pump and on the outer end of the packing ring, consequently the ring is held by the pressure out against the supporting ring and leakage is thus prevented between the flat abutting end faces of the packing and supporting rings. The packing ring described sufficiently packs the joint between the impeller hub and stationary disk or part of the pump and is very durable. If preferred, the internal face of the packing ring can be provided with circumferential grooves

n^s, shown in Fig. 7, which form water seals and aid in preventing leakage. The packing ring is especially designed and intended for use in centrifugal pumps but is not restricted to such use.

A stuffing box or packing gland P of any suitable construction is provided for the impeller shaft at the pressure side of the pump.

Any suitable stuffing box for the shaft at 10 the suction side of the pump may be employed. An ordinary water seal T is shown in the drawings for this purpose.

I claim as my invention:

1. In a centrifugal pump, the combination 15 of a pair of rotary impellers arranged oppositely or with their suction inlets at opposite sides, a casing in which the impellers rotate provided with annular chambers surrounding the impellers into which said impellers discharge, and one or more canals leading from the discharge chamber for the first impeller and passing through the discharge chamber for the second impeller, and a wall provided with one or more return passages 20 which connect the discharge ends of said canals with the suction inlet of the second impeller, substantially as set forth.
2. In a centrifugal pump, the combination 25 of a plurality of pairs of rotary impellers arranged with the suction inlets of the impellers of each pair at opposite sides, a casing in which the impellers rotate provided with annular chambers surrounding the impellers into which said impellers discharge, and one or more canals leading from the discharge chamber for the first impeller of each pair and passing through the discharge chamber for the second impeller of the pair, walls located between the pairs of impellers 30 and beside the second impeller of the last pair and having passages which connect the discharge ends of said canals with the suction inlet of the second impeller of each pair, one of said walls also having passages connecting the discharge chamber for the second impeller of the first pair with the suction inlet for the first impeller of the second pair, substantially as set forth.
3. In a centrifugal pump, the combination 35 of a pair of rotary impellers arranged with their suction inlets at the opposite sides of the impellers, a casing in which the impellers rotate provided with annular chambers surrounding the impellers, parts surrounding the impellers between the same and said discharge chambers and having diffusing passages, one or more canals leading from the discharge chamber for the first impeller and passing through the discharge chamber for 40 the second impeller, and a wall provided with one or more return passages which connect the discharge ends of said canals with the suction inlet of the second impeller, substantially as set forth.
4. In a centrifugal pump, the combination 45 of a plurality of pairs of rotary impellers arranged with the suction inlets of the impellers of each pair at opposite sides of the impellers, a casing in which the impellers rotate comprising a shell and walls located between the pairs of impellers and beside the second impeller of the last pair, parts surrounding the impellers within said shell and having diffusing passages, said shell being provided with continuous annular discharge 50 chambers surrounding said diffusing passages and with one or more canals which lead from the discharge chamber for the first impeller of each pair through the discharge chamber for the second impeller of each pair and join passages provided in said walls to connect the discharge chamber for the first impeller of each pair with the suction inlet of the second impeller of the same pair and the discharge chamber for the second impeller of one pair with the suction inlet of the first impeller of the next pair, substantially as set forth.
5. In a centrifugal pump, the combination 55 of a plurality of rotary impellers, a shaft to which the impellers are secured, a casing in which the impellers rotate comprising a shell and a removable head, walls for separating said impellers and providing connecting water passages therefor, said walls being connected to said removable head and said head together with said shaft, impellers and walls being removable as a unit from said shell, substantially as set forth.
6. In a centrifugal pump, the combination 60 of a plurality of rotary impellers, a shaft to which the impellers are secured, a casing in which the impellers rotate comprising a shell and a removable head, walls for separating said impellers and providing connecting water passages therefor, diffusing rings surrounding said impellers, means connecting all of said walls and diffusing rings to said removable head, said head together with said shaft, impellers, walls and diffusing rings being removable as a unit from said shell, substantially as set forth.
7. In a centrifugal pump, the combination 65 of a plurality of rotary impellers, a shaft to which the impellers are secured, a casing in which the impellers rotate comprising a shell and a removable head, walls for separating said impellers and providing connecting water passages therefor, diffusing rings surrounding said impellers, bolts connecting said walls and diffusing rings to said removable head, and separate means for securing said removable head to said shell, said head together with said shaft, impellers, walls and diffusing rings, being removable as a unit from said shell, substantially as set forth.
8. In a centrifugal pump, the combination 70 of a plurality of rotary impellers, a shaft to which the impellers are secured, a casing in which the impellers rotate comprising a shell 75

and a removable head, removable walls for separating said impellers and providing connecting water passages therefor, seats in said shell for said removable parts, each of which 5 seats is of smaller diameter than the next seat toward the removable head, said removable head and walls being connected, and said head together with said shaft, impellers and walls being removable as a unit from said shell, substantially as set forth.

9. In a centrifugal pump, the combination of a plurality of rotary impellers, a shaft to which the impellers are secured, a casing in which the impellers rotate comprising a shell 15 and a removable head, walls for separating said impellers and providing connecting water passages therefor, diffusing rings surrounding said impellers, seats formed in said shell for said removable parts, each of which 20 seats is of smaller diameter than the next seat toward the removable head, means connecting all of said walls and diffusing rings to said removable head, said head together with said shaft, impellers, walls and diffusing rings being removable as a unit from 25 said shell, substantially as set forth.

10. The combination of a rotary part, a relatively stationary part, a packing ring which surrounds said rotary part, means 30 which hold said packing ring from rotation with said rotary part but allow the ring to

shift laterally, and a support for said holding means which is separate from said stationary part and adapted to be fixed thereto with said holding means in place thereon, 35 substantially as set forth.

11. The combination of a rotary part, a relatively stationary part, a packing ring which surrounds said rotary part, a supporting ring, and means mounted on said supporting ring which hold said packing ring from rotation with said rotary part but allow the packing ring to shift laterally, said stationary part having a seat to receive and hold said supporting ring, substantially as 45 set forth.

12. The combination of a rotary part, a relatively stationary part, a packing ring which loosely surrounds said rotary part, a supporting ring fixed to said stationary part, 50 and means which loosely connect said packing ring to said supporting ring and which hold the packing ring from rotation but allow the ring to be pressed against said supporting ring and to shift laterally and 55 axially, substantially as set forth.

Witness my hand, this first day of December, 1905.

GEORG SULZER.
